RAYMOND L. WHITE, OF INDIANAPOLIS, INDIANA

AUTOMATIC SUCTION BELL AND CURRENT-CONTROL DEVICE

Application filed January 20, 1930. Serial No. 422,107.

This invention relates to an automatic suction bell and current control device.

The chief object of this invention is to provide a device for the intake of mechanisms, such as oil pumps for automobile engines, wherein the same normally is subjected to varying levels of the fluid to be pumped due to varying amounts of liquid and also due to surging of the liquid.

10 The chief feature of the invention consists in providing a directional, intake stream, current controlling mechanism and associating the same with the intake of a pump of the aforesaid character.

15 Another feature of the invention consists in the provision of a suction bell responsive to the suction of the intake and normally constrained toward a predetermined position when not immersed in the liquid to be 20 pumped; in other words, the normal weight of the bell is substantially counterbalanced.

Another feature of the invention consists in the provision of an additional intake to the bell, which under adverse conditions of operation is substantially sealed.

25 A further feature of the invention consists in associating with the bell a sleeve such that the bell and sleeve serve as a valve arrangement operating under predetermined relationship.

The full nature of the invention will be understood from the accompanying drawings and the following description and claims:

In the drawings, Figure 1 is a central sectional view of the device, showing the same embodying a valve control for the intake. Figure 2 is a similar view of a similar construction omitting the valve control of the intake.

40 In the drawings there is illustrated the intake of a pump construction, which herein is shown as upstanding, although the invention may be applied with equal facility to a depending intake, as is well known in the internal combustion engine art.

45 10 indicates the line to the pump; 11 the vertical intake riser terminating in the open mouth 12 and having a plurality of laterally directed apertures 13 annularly arranged and 50 in spaced relation to the open end 12 in the

intake pipe 11. A suction bell having a substantially hemispherical or partially spherical periphery includes an axial and preferably tapered cup 15 and said cup is adapted to seal the open end 12 of the intake pipe. 55 The lower end of the bell through suitable means, such as the straps 16, supports in spaced relation a centrally apertured plate 17, the outer end 18 of which projects substantially horizontal and beyond the open 60 mouth of the bell and is in spaced relation thereto.

In Figure 1 the plate 17 is substantially horizontal throughout and includes a central aperture 19. The pipe 11 supports a plate 65 20 that projects laterally beyond the opening 19 in the first mentioned plate 17 and when the two plates abut, or when the bell is in its lowermost position, the passage between the two plates is completely closed or very ma- 70 terially reduced.

A coil spring 21 is shown bearing at its lower end upon plate 20 and said coil spring is shown as a tension spring; that is, it normally tends to extend and the upper end 75 thereof engages an annular collar 22 that is slidably mounted upon intake pipe 11. Herein said collar is shown of sleeve formation, the same being indicated at 23, and said sleeve through suitable means, such as the straps 24, 80 is secured to the bell and is movable therewith. Herein also a screen 25 is secured at 26 to the open mouth of the bell and at 27 to the sleeve so that all of the liquid received by the intake is screened, as it passes beneath 85 the bell to the intake.

The length of the sleeve 23 is such and the sleeve is so positioned in spaced relation to the cup 15, that when the bell is fully immersed and seated on the end of pipe 12, the 90 open end of said pipe is closed and the apertures 13 are open. When the bell is fully elevated the apertures 13 are closed and the end of the pipe is open. This condition is shown in Figure 1.

In Figure 1 the liquid to be handled is at a considerable height, so that the liquid passes between the mouth of the bell and plate 17 and also passes between the two plates 19 and 20, upwardly and into the open mouth 12, 100

which constitutes an auxiliary intake, the primary intake apertures 13, at this time being closed.

If the level of the liquid to be handled is lowered, which lowering occurs by reason of the consumption of the oil by the engine, the bell falls therewith. This refers to the position of the bell when the engine is not running. When the engine is running, unless there is ice in the engine, the bell always assumes the lowest position.

If the oil supply is sufficiently low, the bell will be in its lowest position and the open end 12 will be sealed and the apertures 13 will be fully opened. At this position the two plates are in substantial abutment and substantially all of the liquid handled passes between the bell and plate 17. In intermediate positions the liquid may be supplied to the bell through the two passages and may be supplied to the pump through the two intakes in varying proportions.

This so-called idle position of the bell is determined by the effective volumetric displacement of the liquid and as a consequence, the position referred to automatically changes with the change in the liquid level, i. e., lowering of the level due to consumption, until either the liquid is so low that the bell rests upon the plate 20, or the level is at least sufficient or greater, such that the bell is fully elevated, as shown in the several figures.

The aperture 19 and the plate 17 permit the liquid to be sucked therethrough in an appreciable amount only when there is a considerable amount of liquid in the crank case or oil chamber in which the device is mounted. As the level of the oil lowers, less oil passes through this auxiliary supply passage and more oil passes through the primary passage between the bell and plate 17. When the bell is elevated the direction of oil intake flow between the two plates 17 and 20 is somewhat horizontal and of course the direction of oil intake flow between the bell and plate 17 is substantially horizontal at all times. When the plate 17 lowers with the bell, the amount of liquid taken through aperture 19 is materially decreased and thus while the directional flow is important, the amount becomes less important, but even this small amount which passes through between the two plates is horizontally directed by reason of a lateral projection or overlapping of plate 20 relative to aperture 19.

Upon the application of suction to the intake pipe 11 by the pump, the bell immediately descends, due to the creation of a vacuum therebeneath, and if the oil is cold the cold oil will roll over the bell and hold it down until the oil gradually warms up, whereupon the bell is permitted to rise slightly until it seeks a natural level. Fuel oil intake is accomplished through the open end of

the pipe when the bell is elevated from the end of the pipe.

Surging of the oil in normal operation of a motor vehicle has little or no effect upon the oil supplied to the intake when the same is equipped with the invention illustrated and described. The plate spreads out the lines of flow and prevents so-called scouring by said lines of flow, which normally takes place in the average device. This scouring action is always observed and is evidenced by a clean pan immediately under the intake of the present day automobile oil pump, showing that in the average engine not equipped with the device illustrated and described herein, the sediment, dirt and the like, as well as water, are introduced into the liquid circulation and re-circulated.

During the winter, in automobile operation, water condensation in the crank case is great and in very cold weather this water freezes, forming ice. The device of the present invention is particularly effective and secures perfect operation in spite of the ice, because when the pump is not working the bell and mechanism supported thereby are in an elevated position, so that the water when it freezes will freeze below the bell and thus the bell will be always effective and will not become frozen in.

In Fig. 2 of the drawings a modified form of the invention is illustrated and in this figure the similar parts are provided with numerals of the 100 series. In this form of the invention, the intake pipe is again shown of the upstanding type. It is not provided with an open end but is provided with a closed end, which is extended as a guide 112. In this form of the invention valve control of the intake is not obtained but all of the advantages beforementioned except that of valve operation are obtained by this form of the device.

This device mechanically performs the ultimate object desired by an oil filter of the cartridge type, because it keeps out of the oil stream the fine grit and sediment that are normally carried with said stream. It does more than that, however, for it is the first mechanical device which is ice-proof. It does more than that as well. It is automatic in that it adjusts itself to the suction and it has a compensating action and travel, due to the association of the several parts and in relation to the suction applied to the counter-balancing spring.

The normal position of the bell is with the plate 17 bearing upon plate 20 when the engine is operating. When not operating, the parts are arranged as illustrated in Fig. 1, for the parts shown in Fig. 1.

One of the objects gained by sealing the end of the tube and uncovering apertures 13, is that the end of the pipe is sealed beneath the cup and the pull is directed laterally for

low positions of the bell instead of upwardly as would be the case if the lateral openings were omitted and the bell were fashioned so that it did not seal the open end of the pipe. 5 Variation in the progressive movement of the bell in its lowering movement is controlled by the shape of the cup 15. The cup is tapered in Fig. 1 and thus the amount of restriction is progressively increased as the bell 10 descends. In this way, the travel of the bell may be controlled insofar as its rate of movement is concerned. In other words, if considerable opposition is to be imposed, the bell 15 would hug rather closely pipe 11. If 15 but little opposition were to be imposed, the cup might be flared outwardly to a considerable extent.

The invention claimed is:—

1. An automatic suction bell and current control device comprising a substantially vertical suction intake pipe including an intake, 20 a dome-shaped suction responsive bell, a guide slideable on said pipe and carried by the bell for guiding the same, an intake current controlling plate supported in spaced relation to the bell and movable therewith, said plate projecting laterally beyond the bell mouth, and means normally urging said bell against immersion, said bell upon the application of 25 suction to the intake moving in opposition to said means.

2. A device as defined by claim 1, characterized by the force for opposing immersion being substantially equal to the normal 30 weight of the bell and bell supported parts.

3. A device as defined by claim 1, characterized by the intake including a laterally directed aperture and said guide comprising a sleeve arranged to vary the effective 40 aperture intake area in bell movement.

4. A device as defined by claim 1, characterized by the intake including an open end upon the pipe and a laterally directed aperture in spaced relation thereto, said guide 45 comprising a sleeve arranged to vary the effective lateral aperture intake area, and said bell including a portion arranged to seal the pipe end when the bell is immersed in opposition to the opposing force.

5. A device as defined by claim 1, characterized by the intake including an open end upon the pipe and a laterally directed aperture in spaced relation thereto, said guide 55 comprising a sleeve arranged to vary the effective lateral aperture intake area, and said bell including a portion arranged to seal the pipe end when the bell is immersed in opposition to the opposing force, said sleeve and 60 pipe sealing bell portion being further arranged so that when the lateral aperture is fully exposed for intake purposes the pipe end is closed and when the aperture is fully closed the pipe end is fully opened.

6. A device as defined by claim 1, characterized by the addition of a screen secured to

the bell adjacent the mouth rim and guide for the purpose described.

7. An automatic suction bell and current control device comprising a substantially vertical suction intake pipe including an intake, 70 a dome-shaped suction responsive bell, a guide slideable on said pipe and carried by the bell for guiding the same, an apertured intake current controlling plate peripherally enveloping the pipe which extends through 75 the plate aperture, said plate being supported in spaced relation to and movable with the bell and projecting laterally beyond the bell mouth, another plate carried by the pipe and arranged to seal the first mentioned plate aperture when the first mentioned plate abuts the same or the bell is in its lowermost position, and means normally urging said bell against immersion, said bell upon the application of suction to the intake moving in opposition to said means. 80

8. A device as defined by claim 7, characterized by the force for opposing immersion being substantially equal to the normal weight of the bell and bell supported parts. 85

9. A device as defined by claim 7, characterized by the intake including a laterally directed aperture and said guide comprising a sleeve arranged to vary the effective aperture intake area in bell movement. 95

10. A device as defined in claim 7, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force. 100

11. A device as defined by claim 7, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force, said sleeve and pipe sealing bell portion being further arranged so that when the lateral aperture is fully exposed for intake purposes the pipe end is closed and when the aperture is fully closed the pipe end is fully opened. 115

12. A device as defined by claim 7, characterized by the addition of a screen secured to 120 the bell adjacent the mouth rim and guide for the purpose described.

13. An automatic suction bell and current control device comprising a substantially vertical suction intake pipe including an intake, a dome-shaped suction responsive bell, a guide slideable on said pipe and carried by the bell for guiding the same, an apertured intake current controlling plate supported in 125 spaced relation to and movable with said bell 130

and projecting laterally beyond the bell mouth, another plate for substantially closing the plate aperture when the first mentioned plate substantially abuts the same or the bell is in its lowermost position, and means normally urging said bell against immersion, said bell upon the application of suction to the intake moving in opposition to said means.

14. A device as defined by claim 13, characterized by the force for opposing immersion being substantially equal to the normal weight of the bell and bell supported parts.

15. A device as defined by claim 13, characterized by the intake including a laterally directed aperture and said guide comprising a sleeve arranged to vary the effective aperture intake area in bell movement.

16. A device as defined by claim 13, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force.

17. A device as defined by claim 13, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force, said sleeve and pipe sealing bell portion being further arranged so that when the lateral aperture is fully exposed for intake purposes, the pipe end is closed and vice versa.

18. A device as defined by claim 13, characterized by the addition of a screen secured to the bell adjacent the mouth rim and guide for the purpose described.

19. A device as defined by claim 1, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force, said sleeve, pipe and bell being arranged for suction intake control and progressive reduction of bell momentum immediately following the application of suction to the intake and initial bell movement thereby.

20. A device as defined by claim 7, characterized by the intake including an open end upon the pipe and a laterally directed aperture in spaced relation thereto, said guide comprising a sleeve arranged to vary the effective lateral aperture intake area, and said bell including a portion arranged to seal the

pipe end when the bell is immersed in opposition to the opposing force, said sleeve, pipe and bell being arranged for suction intake control and progressive reduction of bell momentum immediately following the application of suction to the intake and initial bell movement thereby.

21. A device as defined by claim 13, characterized by the intake including an open end upon the pipe and a laterally directed aperture in spaced relation thereto, said guide comprising a sleeve arranged to vary the effective lateral aperture intake area, and said bell including a portion arranged to seal the pipe end when the bell is immersed in opposition to the opposing force, said sleeve, pipe and bell being arranged for suction intake control and progressive reduction of bell momentum immediately following the application of suction to the intake and initial bell movement thereby.

In witness whereof, I have hereunto affixed my signature.
